United States Patent Office

Des. 233,985
Patented Dec. 24, 1974

233,985

MOTEL ROOM BUILDING

Jimmie L. Jones, Salt Lake City, Utah, assignor to Ute
Indian Tribe of the Uintah and Ouray Reservation,
Uintah County, Utah

Filed May 2, 1972, Ser. No. 249,746

Term of patent 14 years

Int. Cl. D25—03

U.S. Cl. D13—1 B

FIG 3

FIG. 4

FIG. 5

FIG. 6

FIG. 7

FIG. 1 is a perspective view of the motel room building from the front;

FIG. 2 is a similar view from the back;

FIG. 3 is a top plan view thereof;

FIG. 4 is a side elevation of the side indicated by the arrow (FIG. 4) in FIG. 3;

FIG. 5 is a similar view indicated by the arrow (FIG. 5) in FIG. 3;

FIG. 6 is a similar view indicated by the arrow (FIG. 6) in FIG. 3; and

FIG. 7 is a similar view indicated by the arrow (FIG. 7) in FIG. 3.

I claim:

The ornamental design for a motel room building, substantially as shown.
